UNITED STATES PATENT OFFICE.

BRUCE FORD, OF PHILADELPHIA, PENNSYLVANIA.

SECONDARY OR STORAGE BATTERY.

1,271,691.

Specification of Letters Patent. Patented July 9, 1918.

Application filed December 3, 1917. Serial No. 205,024.

To all whom it may concern:

Be it known that I, BRUCE FORD, a citizen of the United States, and a resident of Philadelphia, in the county of Philadelphia and State of Pennsylvania, have invented 5 certain new and useful Improvements in Secondary or Storage Batteries, of which the following is a specification.

The principal object of the present invention is to provide means accessible and operable from the outside of the cover for fastening a filling-and-ventilating stand-pipe to the cover and adapted to permit of rotary adjustment of the stand pipe and of 10 tightening the joint from the outside of the completed cell, without removal of the cover.

The invention will be claimed at the end hereof but will be first described in connection with the embodiment of it chosen from 20 other embodiments for the sake of illustration in the accompanying drawings, in which—

Figure 1, is a top or plan view of a cell 25 embodying features of the invention.

Fig. 2 is a sectional view, taken on the line 2—2 of Fig. 1.

Fig. 3, is a side view, drawn to an enlarged scale, and illustrating the filling- 30 and-ventilating stand pipe.

Fig. 4, is a top or plan view of a locking ring.

Fig. 5, is a similar view of a gasket, and 35 Figs. 6 and 7, are respectively a plan view with the stand pipe removed, and a sectional view taken on the line 7—7 of Fig. 6.

In the drawings 1 is a stand-pipe that can be used for filling and ventilating and 40 2, is a cover provided with an opening 3. There is a right-hand thread on one of these members and a left-hand thread on the other member. The threads are indicated at 4 and 5: 6, is a locking ring having a right-hand thread on one circumference and a left-hand thread on the other circumference to engage the threads 4 and 5 of the members 1 and 2. The opening in the cover is notched as at 7 and there is an 45 outward seat 8 tapped with threads 5, 9, 10 is a packing or gasket provided with notches adapted to be alined with the notches 7. The stand-pipe is provided with feathers 11 and with a shoulder 12 upon which the 55 thread 4 is formed. The gasket 9 is arranged on the seat 8 and it is approximately

of the same outside diameter as the shoulder 12, so that space is afforded at 13 under the locking ring 6. The feathers 11 are arranged in the notches 7 and 10 and the locking ring 6 engages the threads 4 and 5 so that the stand-pipe is rotatively fixed and endwise movable in respect to the cover and the stand-pipe can be adjusted in the present instance, through one hundred and 60 eighty circular degrees in order to shift the position of the fitting 14 by turning the stand-pipe so that the fitting 14 lies in the desired direction prior to the introduction of the feathers 11 in the slots 7. 70

In assembling the parts the gasket 9, which may be of rubber, is first laid in its position on the seat 8 of the cover. The locking ring 6, which may be of hard lead alloy, hard rubber, or the like, is then 75 screwed about one turn onto the thread 4 of the stand-pipe, the latter being preferably a left-hand thread. The stand-pipe with the locking ring on it is then placed upon the cover and the feather 11 on the stand-pipe prevents rotation of the stand-pipe in 80 relation to the cover. The locking ring is then turned right-handed and as the locking ring enters the thread 5 in the cover, it pulls down on the thread 4 on the stand-pipe 85 until the latter reaches and seats upon the rubber gasket. The advantage of doing the work from the top or outside of the cover is that the position of the stand-pipe, or more accurately of the fitting 14, can be 90 changed after the cell is completed without removing the cover, which is somewhat of a job and in case of leakage the parts can be tightened from the outside without the necessity of taking off the cover. 95

It will be obvious to those skilled in the art to which the invention relates that modifications may be made in details of construction and arrangement without departing from the spirit of the invention which 100 is not limited as to those matters or otherwise than as the prior state of the art and the appended claims may require.

What I claim is:

1. In a storage battery having cover and stand-pipe members, the combination of a right-hand thread on one member and a left-hand thread on the other member, and a locking ring having a right-hand thread on one circumference and a left-hand thread 110 on the other circumference to engage the threads of both members.

2. In a storage battery having cover and stand-pipe members, the combination of a right-hand thread on one member and a left-hand thread on the other member, a locking ring having a right-hand thread on one circumference and a left-hand thread on the other circumference to engage the threads of both members, and a feather for preventing relative rotation and permitting relative endwise movement of said members.
- 5 10 15 3. In a storage battery having cover and stand-pipe members, the combination of a right-hand thread on one member and a left-hand thread on the other member, a locking ring having a right-hand thread on one circumference and a left-hand thread

on the other circumference to engage the threads of both members, and a feather for preventing relative rotation and permitting relative endwise movement of said members. 20

4. In a storage battery the combination of a cover provided with a notched opening having an outward tapped seat, a gasket on said seat, a feathered stand-pipe having a threaded shoulder adapted to the gasket 25 with annular space between the thread of the shoulder and the thread of the seat, and an internally and externally threaded locking ring occupying said space and engaging the threads of the shoulder and seat, 30 substantially as described.

BRUCE FORD.
